US00D713134S

(12) **United States Design Patent**
Hardigan et al.

(10) **Patent No.:** **US D713,134 S**
(45) **Date of Patent:** **** Sep. 16, 2014**

(54) **SHOE SOLE**

(75) Inventors: **Henry Hardigan**, Pawtucket, RI (US);
Matthew Montross, Middleboro, MA
(US); **Michael Andrews**, East Falmouth,
MA (US)

(73) Assignee: **Reebok International Limited**, London
(GB)

(**) Term: **14 Years**

(21) Appl. No.: **29/411,762**

(22) Filed: **Jan. 25, 2012**

(51) **LOC (10) Cl.** **02-04**

(52) **U.S. Cl.**

USPC **D2/953**; D2/951; D2/957; D2/960

(58) **Field of Classification Search**

USPC D2/902, 906, 908, 916, 918, 925,
D2/946-962, 977; 36/3 B, 22 R, 24.5, 25 R,
36/28, 32 R, 34 R, 59 C, 67 A, 103

See application file for complete search history.

Primary Examiner — T. Chase Nelson

(74) *Attorney, Agent, or Firm* — Sterne, Kessler, Goldstein & Fox P.L.L.C.

(57) **CLAIM**

The ornamental design for a shoe sole, as shown and described.

DESCRIPTION

FIG. 1 is a top perspective view of a shoe sole showing our new design;

FIG. 2 is a top plan view thereof;

FIG. 3 is a bottom plan view thereof;

FIG. 4 is a left side view thereof;

FIG. 5 is a right side view thereof;

FIG. 6 is a front view; and,

FIG. 7 is a rear view.

1 Claim, 6 Drawing Sheets
